ATTORNEY

UNITED STATES PATENT OFFICE.

JOHANN H. E. SCHMIDT, OF DAYTON, OHIO.

MEAT-CUTTER.

SPECIFICATION forming part of Letters Patent No. 242,843, dated June 14, 1881.

Application filed December 15, 1880. (No model.)

To all whom it may concern:

Be it known that I, JOHANN H. E. SCHMIDT, of Dayton, in the county of Montgomery and State of Ohio, have invented new and useful Im- 5 provements in Meat-Cutters, of which the following is a specification.

My invention relates to the mode of holding the adjusting-board within the knife-frame, and also slotting the ends of the knife to adjust the 10 same within said frame.

The accompanying drawings are made a part of my specification, in which like letters of reference in the different figures designate like parts.

15 Figure I is a slightly-oblique view of the front of the meat-cutter. Fig. II is a front view of the knife-frame.

A represents the frame, which may be varied in construction, the essential features being a 20 groove above and below to support the knife-frame, and a table with a backing to support the meat during the process of cutting.

B represents the knife-frame, which is adapted to move freely within the aforesaid 25 grooves of the frame A. At the front end is a suitable handle to be grasped by the hand during the process of cutting. Near the middle is attached the knife C in diagonal position. The attachment is made by screws G, which enter 30 through horizontal slots H in both ends of the knife. The lengthened slots in the knife serve to adjust the position of the edge of the knife to the adjusting-board, narrowing or widening the space, as circumstances may require. To 35 effect this adjustment the screws are very slightly withdrawn, the knife placed in position, and the screws tightened.

The adjusting-board D occupies the space behind the knife, and its lower part has tongues resting in grooves F F in the lower part of the 40 frame. These grooves admit of a lateral movement, which is adjusted to the thickness of slice it is desirable to cut, and is then secured in position by the thumb-screw E, which is held by a thread within the end of the frame. Ex- 45 perience has shown that the space between the edge of the knife and the edge of the adjusting-board should vary as the thickness of the slice increases or diminishes, and this adjustment is effected by the slots in the knife, as before 50 described.

The operation may be thus described: Place the meat on the table, pressing it against the back and the adjusting-board, the adjustment being made as desirable; then by a forward 55 thrust of the knife-frame a slice of meat is separated. By this means the slicing is done with a uniformity and ease surpassing the usual process.

What I claim as my invention, and desire to 60 secure by Letters Patent, is—

The knife-frame B and knife C, having adjusting-screws G and slots H, in combination with the adjusting-board D, with its binding-screw E, said board being supported in grooves 65 F at base of said frame, substantially as set forth.

JOHANN H. E. SCHMIDT.
